UNITED STATES PATENT OFFICE.

JUDSON L. THOMSON, OF SYRACUSE, NEW YORK.

REIN-HOLDER.

SPECIFICATION forming part of Letters Patent No. 293,819, dated February 19, 1884.

Application filed June 21, 1883. (No model.)

To all whom it may concern:

Be it known that I, JUDSON L. THOMSON, of Syracuse, in the county of Onondaga, in the State of New York, have invented new and useful Improvements in Rein-Holders, of which the following, taken in connection with the accompanying drawings, is a full, clear, and exact description.

This invention relates to the class of rein-holders which grip the rein between two jaws.

The object of this invention is to combine said rein-holder with the whip-socket fastening or clamp in such a manner as to firmly support the rein-holder, and at the same time carry the same a proper distance from and in such position in relation to the whip-socket as to admit of placing the latter in the usual proximity to the dash-board, and also to greatly facilitate the application of the rein to the rein-holder.

The invention consists, essentially, in the combination, with a whip-socket clamp, of an arm integral therewith and projecting laterally therefrom, and a rein-holding clamp secured to the free end of said arm, all as hereinafter more fully described, and set forth in the claim.

The annexed drawings illustrate several exemplifications of the embodiment of the invention.

Figures 1 and 2 are perspective views of two styles of whip-socket attachments combined with different forms of rein-holders. Fig. 3 is a perspective view of another style of whip-socket attachments, with the rein-holder proper broken away; and Figs. 4 and 5 are plan views, illustrating further modifications of the invention.

Like letters of reference indicate like parts in all the figures.

A denotes that part of the whip-socket attachment which encompasses the whip-socket, and B is the part by which it is clasped onto the rail of the dash-board frame. The part B is usually in the form of jaws *a a*, which are either integral with or otherwise attached to the part A, as shown in Figs. 1, 2, 4, and 5 of the drawings, the part A being in the form of an expansible ring, which is some-

times composed of two parts, as shown in Figs. 1 and 5 of the drawings, and sometimes made of one piece of flexible material, as illustrated in Figs. 2 and 4 of the drawings. A bolt, *b*, passing transversely through the junction of the jaws *a a* with the ring A, serves to draw the said ring tightly around the whip-socket and simultaneously clamp the jaws onto the rail of the dash-board frame. In some instances the part A consists of a solid ring, as shown in Fig. 3 of the drawings, said ring being formed on one side with a bar, *c*, which is fitted to the back of the dash-board rail, a similar bar, *d*, being applied to the opposite side of said rail, and screws or rivets passing through the ends of the said bars fasten the device to the dash-board.

It will be observed that in the cases where the ring A is expansible the jaws *a a* are generally the firmest and heaviest parts, and therefore I prefer to attach the rein-holder to said jaws; but where the ring A is solid, as shown in Fig. 3 of the drawings, the rein-holder may be attached thereto at any eligible or desired position.

C represents the rein-holder-sustaining arm, which projects laterally from the before-described whip-socket clamp or fastening, and is made integral therewith; and D is the rein-holding clamp secured to the free end of said arm, the latter being made of proper length to carry the rein-holder D away from the whip-socket a sufficient distance to allow the said socket to be fastened in the usual proximity to the dash-board. The aforesaid position of the rein-holder also allows the rein to be thrown around the side edge of the dash-board and drawn into the rein-holding clamp, without necessitating the removal of the whip from the socket or entailing the inconvenience of reaching around the whip in the socket and carrying around it the end of the rein.

I am aware that a stem has been applied directly to the whip-socket clamp for the purpose of holding the rein; but it is obvious that such a device requires increased distance between the whip-socket and dash-board, and also necessitates either the removal of the whip from the socket or the passing of the rein

around the whip in order to apply the rein to the rein-holder; hence such a device does not accomplish the object of my invention.

Having described my invention, what I claim as new, and desire to secure by Letters Patent, is—

The combination, with a whip-socket clamp, of an arm integral therewith and projecting laterally therefrom, and a rein-holding clamp secured to the free end of said arm, substantially in the manner described and shown.

In testimony whereof I have hereunto signed my name and affixed my seal, in the presence of two attesting witnesses, at Syracuse, in the county of Onondaga, in the State of New York, 15 this 14th day of June, 1883.

JUDSON L. THOMSON. [I. S.]
